UNITED STATES PATENT OFFICE.

WILLIAM F. DRAPER, OF HOPEDALE, MASSACHUSETTS.

SUPPORT FOR SPINNING-SPINDLES.

SPECIFICATION forming part of Letters Patent No. 391,462, dated October 23, 1888.

Application filed March 9, 1888. Serial No. 266,730. (No model.)

To all whom it may concern:

Be it known that I, WILLIAM F. DRAPER, of Hopedale, county of Worcester, State of Massachusetts, have invented an Improvement 5 in Supports for Spinning-Spindles, of which the following description, in connection with the accompanying drawings, is a specification, like letters on the drawings representing like parts.

This invention has for its object to improve 10 the bearings of that class of spindle having a sleeve-whirl and wherein all the bearings are located below the junction of the whirl and spindle.

In another application made by me, Serial 15 No. 261,035, I have shown a bolster-case provided with a bolster having rolling-surfaces, and in an application, Serial No. 266,729, I have shown such a bolster mounted in a bolster-tube loose in the bolster-case. Herein I 20 have shown a bolster-case provided with one loose bearing and with one bearing having rolling-surfaces, both inclosed in a bolster case or support.

My invention consists, essentially, in a bolster case or holder and a sleeve-whirl spindle, combined with a divided or compound bolster, one part of which is mounted loosely in the bolster case or holder, while the other part contains a series of rolling-surfaces, such construction 25 enabling the spindle to be supported in such manner as to vibrate below its connection with the whirl, to thus accommodate for uneven loading and avoid jarring or chattering, the rolling-surfaces reducing the friction 30 between the parts, thus enabling the spindle to attain high speed with the expenditure of but little power.

Figure 1 in vertical section shows a spindle embodying my invention, the spindle being in 40 elevation with the whirl in section. Fig. 2 is a section below the line x , Fig. 1. Fig. 3 is a section in the line y , Fig. 1, looking down. Fig. 4 shows a modified form of my invention with the spindle broken off above the whirl; 45 Fig. 5, a section below the line x' ; and Fig. 6 shows the spider by itself.

The rail A, the bolster case or support B, the nut C, and the spindle D, having the sleeve-whirl D', are and may be all as usual.

50 The bolster case or support receives within it a divided or compound bolster composed of

a tube-like portion, a , in which the spindle below the wheel has a running fit, and a portion, as b , having a series of rolling-surfaces, the said rolling-surfaces being herein shown 55 as short cylinders held by a spider, as c , (shown separately in Fig. 6,) the said rolls and spider being common to my application, Serial No. 261,035.

In Fig. 1, the sleeve-like bolster portion has 60 a collar or flange, a' , at top to rest upon the bolster case or support near its upper end, the said portion being therein shown surrounded by an elastic or yielding packing or jacket, d . The head or flange of the portion a has a notch, 65 (see Fig. 7,) which is entered by a lug or projection at the upper end of the bolster case or support to thus prevent the rotation of the portion a . The outside of the spindle bears against the rolling-surfaces, and the latter fit 70 the space between the spindle and the inner wall of the bolster case or support.

In Fig. 4, I have shown the portion of the bearing having rolling-surfaces as located 75 near the upper end of the bolster-case rather than near its lower end, as in Fig. 1, the bearing portion a , bored to receive and fit the spindle, being restrained from rotation by a pin or projection, e , the said portion a in Fig. 4 being shown as bored for but part of its length, 80 so as to form a step-bearing.

In this invention the rolls located between the spindle and the rigid case or support outside of it, and also within the sleeve-whirl, and substantially in the line of the band-pull, lessen 85 friction between the spindle and its surrounding bearing, while the loose or yielding portion, as a , moves to accommodate for the vibration of the spindle under an unbalanced load.

Instead of the fibrous packing, cork or metallic springs, or any usual means for enabling the bearing to move against an elastic pressure, may be used without departing from my invention, and would be within the scope of the 95 term "elastic packing."

I claim—

1. The bolster case or support and the sleeve-whirl spindle, combined with a double or compound bearing, consisting of a sleeve-like portion, a , fitting the spindle, and a portion, b , having rolling-surfaces, both the said 100

bearing portions being located within the said bolster case or support, substantially as described.

2. The bolster case or support and the sleeve-whirl spindle, combined with a double or compound bearing, consisting of a sleeve-like portion, *a*, fitting the spindle and loose in the said case or support, means to prevent it from rotation with the spindle, and a portion, *b*, having rolling-surfaces, both the said bearing portions being located within the said bolster case or support, substantially as described.

3. The bolster case or support and the sleeve-whirl spindle, combined with a double

or compound bearing, consisting of a sleeve-like portion, *a*, fitting the spindle and loose in the said case or support, and the surrounding elastic or yielding packing, and a portion, *b*, having rolling-surfaces, both the said bearing portions being located within the said bolster case or support, substantially as described.

In testimony whereof I have signed my name to this specification in the presence of two subscribing witnesses.

WM. F. DRAPER.
